UNITED STATES PATENT OFFICE.

TERESSA A. BLAIR, OF MARQUAM, OREGON.

BANDAGE-ROLLING MACHINE.

1,359,021.

Specification of Letters Patent.

Patented Nov. 16, 1920.

Application filed March 27, 1918. Serial No. 225,053.

To all whom it may concern:

Be it known that I, TERESSA A. BLAIR, a citizen of the United States, residing at Marquam, in the county of Clackamas and State of Oregon, have invented certain new and useful Improvements in Bandage-Rolling Machines; and I do hereby declare the following to be a full, clear, and exact description of the invention, such as will enable others skilled in the art to which it appertains to make and use the same.

This invention relates to improvements in bandage rolling machines and has for one of its objects the provision of a device of this character whereby a strip of bandage may be readily and conveniently wound into a roll, so that the same can be conveniently applied to wounds.

Another object of this invention is the provision of a spindle having means connected thereto for supporting and rotating the same so that a strip of bandage material may be readily wound thereon and which can be disconnected from said means after the bandage has been rolled, so that the roll can be removed from said spindle.

A further object of this invention is the provision of a bandage rolling machine of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawing, in which:—

Figure 1 is a side elevation of a bandage rolling machine constructed in accordance with my invention,

Fig. 2 is a vertical sectional view of the same,

Fig. 3 is a transverse sectional view illustrating an internal gear meshing with a pinion carried by a drive shaft,

Fig. 4 is a fragmentary vertical sectional view of the means for connecting the spindle to the driving shaft, and

Fig. 5 is a plan view of a disk.

Referring in detail to the drawing, the numeral 1 indicates a vertical upright having formed upon its lower end a pair of relatively spaced lugs 2 which are adapted to engage the upper and lower faces of a table or like support 3. The lower lug is provided with a screw threaded opening to receive a set bolt 4 provided with a head 5 and a handle 6, which head is adapted to be turned into engagement with the table or support 3 by turning the set bolt 4 by the handle 6 to tightly clamp the support to the upper lug 2. The horizontally disposed bearing 7 is formed upon the upper end of the vertical upright 1 and has journaled therein a shaft 8 carrying at one end a pinion 9. The pinion 9 is in mesh with an internal gear 10 journaled to a stub shaft 11 secured to the vertical upright 1. The internal gear 10 has secured thereto a handle 12 for the purpose of rotating the same so that the shaft 8 may be rotated.

The other end of the shaft 8 has formed thereon an enlarged head 13 provided with a hexagonal opening or socket adapted to removably receive a hexagonal shaped spindle 14 and which is detachably secured within the socket by means of a set screw 15, carried by the head 13. A circular disk 16 is provided with a hexagonal opening 17 to receive the spindle 14 and is moved in engagement with the head 13 so that bandages when wound upon the spindle will not come in contact with the head 13 and thereby be prevented from becoming mutilated or the edges of the material crimped.

In operation, the device is secured to a support or table top and a strip of bandage material is then wound about the spindle 14 once or twice and the operator then holds the material in one hand permitting it to move freely through the fingers and rotate the internal gear 10 by the handle 12 which drives the spindle 14 winding the material thereon.

The spindle 14 being of hexagonal shape causes the strip of material to readily wind thereon without slipping. By holding the strip of bandage material in one hand and permitting the same to move or slide freely through the fingers, the same can be readily fed on to the spindle 14 by rotating the gear 10 by the handle 12. The bandage material is first turned manually several times about the spindle before the regular operation of

the machine is started. After the entire strip of bandage material has been wound upon the spindle 14, in roll form, the roll is gripped by the fingers of the operator and 5 the spindle 14 is turned slightly in a reverse direction by turning the handle 12 in a reverse direction thereby loosening the roll of bandage material upon the spindle. The operator then places the fingers of one hand 10 against the disk 16 and pulls the disk off of the spindle 14 carrying with the same a roll of bandage material. By removing the roll of bandage material from the spindle in the above manner prevents the edges of the material 15 from being crimped or mutiliated. After the roll of bandage material has been removed by sliding the disk 16 off of the spindle 14, the disk is again placed on the spindle 14 as illustrated in Fig. 2 placing 20 the device ready for the next operation of the machine. The disk 16 is so mounted upon the spindle 14 that the same can be readily removed and replaced upon the spindle when desired.

25 While I have shown and described the preferred embodiment of my invention, it will be understood that minor changes in construction, combination, and arrangement of parts, may be made without departing from

the spirit and scope of the invention as 30 claimed.

Having thus described my invention, what I claim as new is:—

A bandage rolling machine comprising a vertical support, a horizontal bearing formed 35 on the upper end of said support, a shaft journaled in said bearing, a head formed on one end of said shaft and having a socket provided with squared faces, a spindle having squared faces and fitted in said socket, 40 a disk slidable on said spindle and normally engaging the head to prevent a bandage from engaging a head when being wound on said spindle and adapted to be manually slid on said spindle in the direction of its 45 free end to remove a roll of bandage therefrom without crimping the edges of said bandage, a gear secured to the other end of the shaft, an internal gear journaled to the support below the bearing and in mesh with 50 said gear, and a handle secured to said internal gear.

In testimony whereof I affix my signature in presence of two witnesses.

MRS. TERESSA A. BLAIR.
